BATH IMPLEMENT

Joseph Delle Chiaie, Clifton, N. J.

Application March 19, 1945, Serial No. 583,404

4 Claims. (Cl. 299—67)

1

This invention relates to bath appliances and it has for its object to provide an appliance which will act to spray the skin surface and at the same time effect scrubbing of such surface by rotation of the part which acts to spray; which may be inexpensively constructed and light in weight, as when mainly composed of some plastic material; and whose parts are readily capable of being assembled and disassembled.

In the drawings,

Fig. 1 is a view of the appliance partly in vertical section, partly in elevation and partly shown by dotted lines;

Fig. 2 is a view showing fragments of the propeller and upper spray-head section, the latter in elevation and the former in section;

Fig. 3 is a view of the appliance mainly in section in a horizontal plane cutting the propeller;

Fig. 4 is a fragmentary plan of the upper spray-head section; and

Fig. 5 shows the post 3 and bottom wall of the body part respectively in side elevation and in section.

The said body part 1 of the cylinder or housing is divided by a horizontal wall 2 into an upwardly open upper chamber 1a and a downwardly open lower chamber 1b, the latter being here appreciably shallower than chamber 1a. Upstanding from wall 2 is a central tubular post 3 having a port 3a here near wall 2, to permit flow of water from space 1a to the bore 3b of the post. A water-admitting nozzle 4 projects from the body part of the housing in tangential relation thereto and is corrugated externally, as at 4a, so as to receive and form a sealing fit with a rubber hose suitably connected with a supply-faucet. The cylinder or housing is completed by a cover or end wall 5 having a central opening 5a and a depending outer flange 5b which fits snugly over the upper margin of said body part 1 and may be detachably connected therewith in any way, as by a bayonet-joint formed by studs, such as 6, on said body part and angular slots 7 in said flange 5b.

Rotating in the cylinder or housing thus formed is a propeller and this carries a hollow spray-head here formed in two superposed sections which together provide a water chamber a, the lower section having a central water-intake port and the upper section having groups of interspersed spray-outlets and upstanding brush bristles.

The propeller includes a tubular stem 8 which penetrates and closely fits opening 5a in cover 5 and is journaled on and snugly fits the post 3 and

rests at its lower end on wall 2, and at such lower end has a series of notches 8a forming ports adapted on rotation of the propeller to register with the port 3a successively, to admit to the passage formed by the bores of the port and stem water inflowing via the nozzle. The propeller also includes blades 9 radially projecting from its stem and contained in chamber 1a.

The lower section of the spray-head is a shallow receptacle 10, open at the top, its upper or outer marginal flange 10a having approximately the same diameter as the flange 5b of the cover 5, and said receptacle having a central opening 10b surrounded by a flange 10c which depends through the opening 5a in cover 5 and is snugly fitted to the stem 8, to which it is detachably connected in some way, as by a bayonet-joint formed by studs, such as 8b, on said stem and angular slots 10a in flange 10c. The upper section 20 of the spray head is an inverted shallow member 12 whose depending marginal flange 12a fits snugly in the flange 10a of the receptacle 10 and to which it is detachably connected, here as by a bayonet-joint formed by studs, as 13, on its flange 12a and angular slots 14 in the flange 10a. The horizontal or top wall of this section is provided with spray-outlets 15 and upstanding brush-bristles 16, interspersed in some way, as by being arranged in radial groups alternating with each other, as shown in Fig. 4.

The lower chamber 1b of body part 1 is to receive a disk-shaped cake of soap 17 snugly and hence firmly established therein.

So long as the cover 5 remains interlocked at 35 6—7 with the body part of the cylinder or housing and so long as the spray-head is interlocked, as at 8b—10d with the stem 8, or so that the spray-head and the propeller remain a unit, such unit will be confined against upward displacement from the cylinder or housing by contact of the propeller blades with said cover, as shown in Fig. 1.

When water is admitted via intake 4 and enters chamber 1a it rotates the propeller and as its ports successively pass the post 3a the water flows into and up through post 3 and stem 8 into the water-chamber a of the spray-head from whence it issues via the spray-outlets 15 of the latter. Meanwhile the unit formed by the spray-head 50 and the propeller is rotated by the water circulating in the housing, wherefore the brushing action of the spray-head is rotative. By inverting the appliance the soap-cake 17 may be applied to the skin.

If, as indicated, the appliance is to be formed

generally of some light and inexpensive material, as of plastic, and if access to the propeller is at any time to be had, such advantages will be possible if, as shown, the parts are separable.

Having thus fully described my invention what I claim is:

1. A spraying implement including a housing substantially in the form of a right circular cylinder, the housing providing a liquid chamber therewithin, said housing having a liquid intake connected thereto, said housing having a rear end wall and a forward end wall spaced from the rear end wall, the end walls being located in planes substantially at right angles to the axis of the cylindrical wall of the housing, the rear end wall having a bearing substantially centrally thereof, the front wall of the housing having a central opening, a propeller within the housing, said propeller comprising a central hollow shaft coaxial with the housing and blades affixed thereto, the rear end of the shaft being supported by the bearing on the rear end wall of the housing, there being at least one opening in the propeller shaft, said opening communicating with the liquid chamber in the housing, a chambered spray-head, having spray-outlets on its forward end wall around the axis of the housing, connected to the forward end of the central propeller shaft, said spray-head being in the form of a hollow disc of right circular cylindrical shape and of substantially the same diameter as the housing, the spray-head being connected coaxially of the propeller shaft and housing, the rear end wall of the spray-head lying parallel to and close to the forward end wall of the housing, the rear end wall of the spray head having an opening centrally thereof, means at the opening in the rear end wall of the spray-head forming a joint connecting the spray-head to the forward end of the hollow propeller shaft, the central opening in the forward end wall of the housing forming a bearing supporting the forward end of the propeller shaft and the spray-head.

2. A spraying implement including a housing substantially in the form of a right circular cylinder, the housing providing a liquid chamber therewithin, said housing having a liquid intake connected thereto, said housing having a rear end wall and a forward end wall spaced from the rear end wall, the end walls being located in planes substantially at right angles to the axis of the cylindrical wall of the housing, the rear end wall having substantially centrally thereof an inwardly facing bearing member normal thereto, the bearing member extending inwardly of the housing for but a portion of the distance between the end walls of the housing, the front wall of the housing having a central opening, a propeller within the housing, said propeller comprising a central hollow shaft coaxial with the housing and blades affixed thereto, the rear end of the shaft telescoping the bearing member on the rear end wall of the housing, there being at least one opening in the propeller shaft, said opening communicating with the liquid chamber in the housing at one point in the revolution of the shaft, a chambered spray-head, having spray-outlets on its forward end wall around the axis of the housing, connected to the forward end of the central propeller shaft, said spray-head being in the form of a hollow disc of right circular cylindrical shape and of substantially the same diameter as the housing, the spray-head being connected coaxially of the propeller shaft and housing, the rear end wall of the spray-

head lying parallel to and substantially contacting the forward end wall of the housing, the rear end wall of the spray-head having an opening centrally thereof, means at the opening in the rear end wall of the spray-head forming a joint connecting the spray-head to the forward end of the hollow propeller shaft, said joint extending through and snugly fitting the central opening in the forward end wall of the housing to form a bearing supporting the forward end of the propeller shaft and the spray-head.

3. A spraying implement including a housing substantially in the form of a right circular cylinder, the housing providing a liquid chamber therewithin, said housing having a liquid intake connected thereto, said housing having a rear end wall and a forward end wall spaced from the rear end wall, the end walls being located in planes substantially at right angles to the axis of the cylindrical wall of the housing, the rear end wall having substantially centrally thereof an inwardly facing tube normal thereto, the tube extending inwardly of the housing for but a portion of the distance between the end walls of the housing, the front wall of the housing having a central opening, a propeller within the housing, said propeller comprising a central hollow shaft and blades affixed thereto, the rear end of the shaft telescoping the tube on the rear end wall of the housing, the propeller shaft and the tube having at least one opening in each, said openings communicating with each other, the bore in the hollow shaft, and the liquid chamber in the housing, at one point in the revolution of the shaft, a chambered spray-head, having spray-outlets on its forward end wall around the axis of the housing, connected to the forward end of the central propeller shaft, said spray-head being in the form of a hollow disc of right circular cylindrical shape and of substantially the same diameter as the housing, the spray-head being connected coaxially of the propeller shaft and housing, the rear end wall of the spray-head lying parallel to and substantially contacting the forward end wall of the housing, the rear end wall of the spray-head having an opening centrally thereof, means at the opening in the rear end wall of the spray-head forming a joint connecting the spray-head to the forward end of the hollow propeller shaft, said joint extending through and snugly fitting the central opening in the forward end wall of the housing to form a bearing for the forward end of the propeller shaft.

4. A spraying implement including a housing substantially in the form of a right circular cylinder, the housing providing a liquid chamber therewithin, said housing having a liquid intake connected to the sidewall thereof substantially tangentially to such sidewall, said housing having a rear end wall and a forward end wall spaced from the rear end wall, the end walls being located in planes substantially at right angles to the axis of the cylindrical wall of the housing, the rear end wall having substantially centrally thereof an inwardly facing tube normal thereto, the tube extending inwardly of the housing for but a portion of the distance between the end walls of the housing, the front wall of the housing having a central opening, a propeller within the housing, said propeller comprising a central hollow shaft and generally radial blades affixed thereto, the rear end of the shaft telescoping the tube on the rear end wall of the housing, the propeller shaft and the tube having at least one

opening in each, said openings communicating with each other, the bore in the hollow shaft, and the liquid chamber in the housing, at one point in the revolution of the shaft, a chambered spray-head, having spray-outlets on its forward end wall around the axis of the housing, connected to the forward end of the central propeller shaft, said spray-head being in the form of a hollow disc of right circular cylindrical shape and of substantially the same diameter as the 10 housing, the spray-head being connected coaxially of the propeller shaft and housing, the rear end wall of the spray-head lying parallel to and substantially contacting the forward end wall of the housing, the rear end wall of the spray-head having an opening centrally thereof, a flange surrounding the opening in the rear end wall of the spray-head, said flange being normal to such rear end wall of the spray-head and directed into the opening in the forward wall of the housing, said 20

flange surrounding the forward end of the central propeller shaft, the flange extending through and snugly fitting the central opening in the forward end wall of the housing to form a bearing for the forward end of the propeller shaft.
